UNITED STATES PATENT OFFICE.

ROBERT THOMAS JENNEY, OF LONDON, ENGLAND, ASSIGNOR TO THE
LAMSON CONSOLIDATED STORE SERVICE COMPANY, OF NEWARK,
NEW JERSEY.

DESIGN FOR A TUBULAR CONNECTION FOR PNEUMATIC-DESPATCH TUBES.

SPECIFICATION forming part of Design No. 33,432, dated October 23, 1900.

Application filed September 22, 1900. Serial No. 30,859. Term of patent 14 years.

To all whom it may concern:

Be it known that I, ROBERT THOMAS JENNEY, a citizen of the United States, residing at London, England, have invented and produced a new and original Design for a Tubular Connection for Pneumatic-Despatch Tubes, of which the following is a specification, reference being had to the accompanying drawings, forming part thereof.

Figure 1 is an elevation of a tubular connection of my new design, and Fig. 2 is an end view of same.

The leading features of my design comprise a tubular connection having reversely-curved portions and a neck extending laterally from one end of one of the portions. Thus the curved portion 1 has a neck 2 extending laterally from one end, and the reversely-curved

portion 3 extends from the other end, and socket portions 4 5 project from one end of the neck portion 2 and the reversely-curved portions 3. The portions 1, 2, and 3 are ornamented on their sides with raised pattern-work 10, separated by a plain portion 11.

What I claim is—

The design for a tubular connection for pneumatic-despatch tubes, substantially as shown and described.

In testimony whereof I have hereunto set my hand in the presence of two subscribing witnesses.

ROBERT THOMAS JENNEY.

Witnesses:

PHILIP M. JUSTICE,
EDWARD TRUMP FOSTER.
